Figure 9c is a view illustrating the connection of chain
81 to the receiver.

Figure 10 is a partial view of the left hand side of the
loom illustrating the manner in which the carrier picks
up a fresh filler thread.

Figure 11 is a view similar to Figure 10 further illus-
trating the action in picking up of a filler thread.

Figure 12 is a plan view of the right hand side of a
loom illustrating the temple plate.

Figure 13 is a partial front view of the loom illustrating
the heddle arrangement for the filler threads.

Figure 14 is a view of a heddle operating means for
filling yarns.

Figure 15 is a front view of a loom.

Figure 16 is a side view of the loom of Figure 15.

Figure 17 is a detail showing the main crank of the
loom.

Figure 18 is a view illustrating an alternative manner
of arranging the supply of filler thread.

Figure 19 is a side view of a shuttle employed with the
loom.

Figure 20 is an end view of a receiver with a carrier
therein.

Figure 21 is a view on line 21—21 of Figure 19.

Figure 22 is an end view of the shuttle of Figure 19
with the carrier deposited within the jaws thereof.

Figure 23 is a view showing the component parts of
the carrier that fit within the body member.

Figure 24 is a horizontal cross section through the
carrier further showing the component parts in assembly
within the body member.

Figure 25 is a view of the right hand side of the loom
showing the selvedge edge cutting knife, and the receiver
and the cam mechanisms for operating them.

Figure 26 is a view of the right hand side of the loom
with the frame removed, to show the receiver and air
blast mechanisms.

Figure 27 is a view of the cam for operating the
receivers.

Figure 28 is a top view of the right hand side of the
loom.

Figures 29 to 32 are partial views of the receiver
showing how the carrier is operated therein.

Figure 33 is a side view of the receiver.

Figure 34 is a plan view of the receiver.

Figure 35 is a plan view of the left hand side of the
loom showing the first phase in the picking up of the
filler thread.

Figures 36 and 37 further show the picking up and
cutting of the filler thread as the lay moves forward.

Figure 38 is a side view showing the temple on the
left hand side of the loom.

Figure 39 is a schematic view illustrating the weaving
of cloth.

Referring to the drawings and first to the loom shown
in Figures 1 to 14, the numeral 10 indicates the frame
of a loom. Within the frame there is mounted a lay 11
which is reciprocated between the rearward position of
Figure 1 and the forward position of Figure 2 by means
well known in the art and not illustrated in the applica-
tion.

The shuttle is caused to travel back and forth across
the lay in the usual fashion and can be actuated by any
pick motion.

This particular application does not deal with pick
motions and it is not thought necessary to illustrate the
one used in this loom, because of their general recogni-
tion in the art.

The warp threads are fed through heddles from beam
12 in the usual manner and detailed illustration of this is
not thought necessary.

The application is concerned with the filling or weft

This invention relates to a loom, and to a method of
weaving more particularly it relates to an improvement
in a loom and to a method of weaving in which the
filler threads are continuously and selectively fed to the
shuttle through heddles from spools. It is a continuation
in part of my co-pending application Serial Number
590,187 filed on the 8th of June 1956 now abandoned.

It is customary when weaving fabrics to supply the
filler threads from bobbins associated with the shuttle.
I have devised a means and method for feeding filler
threads continuously through heddles from a spool. With
my loom method of weaving it is possible to provide for
a great variety of color in the filler threads, which
variety is only limited by the heddle arrangement em-
ployed for the filler threads.

Generally speaking I feed the filler threads from a
continuous supply to a carrier as it is held in receivers
and incorporate means in the shuttle for transferring the
carrier between the two receivers at each side of the loom.
The filler threads so incorporated into the cloth are packed
in the usual way. My loom and method of weaving will
be apparent after reading the following detailed specification
read in conjunction with the drawings.

In the drawings:

Figure 1 is a side view of a loom illustrating principal
parts only and showing the lay in its rearward position.

Figure 2 is a similar view to Figure 1 but showing the
lay in its most forward position.

Figure 3 is a side view of the shuttle, the carrier and
the receiver.

Figure 3a is a perspective view of the carrier showing
how it grips and cuts one filler thread and picks up a
new filler thread.

Figure 4 is a view of the middle portion of the shuttle
showing the manner in which it grips the filler thread
carrier during the operation of the loom just prior to
when the carrier is deposited by the shuttle in the carrier
receiver, which is mounted on the lay.

Figure 5 is a similar view to Figure 4 illustrating the
carrier in the receiver just prior to being picked up by
the grippers of the shuttle and taken to the opposite side
of the lay.

Figure 6 is a sectional view along the line 6—6 of
Figure 4 with the filler thread carrier removed.

Figure 7 is a detailed plan view illustrating the carrier
member and the bifurcated end of the carrier receiver.

Figure 7a is a section along the line 7a—7a of Figure 7.

Figure 7b is a section along the line 7b—7b of Figure 7.

Figure 8 is a detail illustrating the cam arrangement for
operating the means for reciprocating the carrier receiver
in operation and for operating the air blast means for
the blowing in of the free ends of the selvedge edge of
the fabric.

Figure 9 is a view illustrating one end of the loom,
it being appreciated that the opposite end is the same
in form.

Figure 9a is a view along the line 9a—9a of Figure 9.

Figure 9b is a view along the line 9b—9b of Figure 9.

threads and the means for feeding them. The filling threads are fed from spools 13 at each side of the loom through filling thread heddles 14 to a carrier that is moved by the shuttle generally indicated by the numeral 15 for incorporation into the cloth.

The lay 11 carries the usual reed 16 for beating the picks of filling threads after they have been carried across the fabric between the warp threads by the shuttle. This beating operation is achieved by a forward motion of the lay 11 after the shuttle has traversed it with a pick of tensioned filling thread. The mechanism for moving the lay with its reeds is not illustrated since it is well known.

The shuttle in my loom has a longitudinally extending channel 15a within which is mounted a gripper for the filling thread carrier member.

The gripper comprises a body portion 17 having a rigid jaw 17a and a movable jaw 18 pivotally mounted as at 18a cooperating with the jaw 17a. The jaw 18 is spring held towards a closed position as illustrated in Figure 6 by means of the bolt 19 and the compression spring 20. Bolt 19 passes through a hole in jaw 18 and spring 19 is compressed between the body 17 and nut on bolt 19 as illustrated. A hole is bored in the shuttle 15 to accommodate nut and bolt combination 19 as indicated. Jaw 18 is yieldable for movement to the left as viewed in Figure 6 to an open position against the tension of spring 20 in use.

The carrier, generally indicated by the numeral 21 comprises a body 22 having a groove extending longitudinally thereof, within which sits a resilient of fibre filling thread locking plate 24a. A pin 23b extends from the grooved side wall 23c of the body 22 and through the fibre locking plate 24a. The bar or hook member 23 is formed with a hook at each end thereof and with a longitudinally extending slot 23a to permit it to slide about the pin 23b within the groove. Cutting blade 24 has a cutting edge at each end thereof and is mounted in the groove to overlay the ends of the bar 23. The operation of the carrier will be described later.

A carrier receiver is mounted adjacent each end of the lay and is generally indicated by the numeral 25. It is reciprocably mounted and can be moved inwardly and outwardly of the shed by means of the spring loaded actuating means 25a and the cam mechanism generally indicated by the numeral 26.

The warp threads 30 are fed to the fabric in the usual manner through heddles 30a from beam 12.

The filling threads are fed from spools 13 through tension bracket 13a and heddles 14. The tension bracket 13a is adapted to keep the filling threads in even tension and assure a consistent beating of the filling thread by the packing reed 16.

In use, the shuttle 15 is caused to reciprocate across the lay which can be of conventional design.

As the shuttle travels across the loom the channel 15a of the shuttle 15 passes over the carrier receivers 25 and, as it does so, the carrier member 21, which is formed with teeth and is gripped between the jaws 17a and 18 of the shuttle gripper, engages with the bifurcated end of the carrier member and is deposited therein.

In this latter connection the carrier member gripping jaws of the shuttle co-operate with the receiver and are opened thereby as they encounter it. It will be noted that the carrier receiver members 25 are provided with sloped surfaces and roller bearings 31 which function to open the yieldable jaw 18 of the gripper of the shuttle 15 whereby to release the carrier 22.

The carrier receiver 25 has a reduced depth inwardly of its free end as indicated at 33 to permit the movable jaw 18 to assume its normal position, as illustrated in Figure 6, under the tension of the spring 20, when the shuttle has moved sufficiently therealong in use to clear the free end portion of the carrier 25 that is of increased depth. The portion of the carrier receiver of increased depth is adapted to open the jaw 18 whereby it releases

the carrier member 21 as it deposits it in the bifurcated end of the receiver 25 as the shuttle enters the shuttle box.

It will be appreciated that both ends of the loom are similar structurally and operationally.

The operation of the loom is as follows: let it be assumed that the side picker has just hammered the shuttle 15 with the carrier 21 in the gripper thereof from the right hand side of the loom to the left hand side of the loom as viewed from the front in Figure 13. A filling thread 34 from the filling thread spool 13 on the right hand side of the loom is locked between one of the ends of the hook 23 and the filling thread locking piece or shoe 24a.

In Figure 4 the shuttle 15 is illustrated approaching the bifurcated end of the carrier receiver 25. The elongated channel 15a of the shuttle 15 is adapted to pass over the receiver and, as it does so the carrier 21 enters the bifurcated end of the carrier receiver 25 and the jaw 18 of the gripper of the shuttle 15 engages the sloping portion of the bifurcated end of the carrier receiver 25, whereby it is caused to open and to release the carrier 21 and leave it in the bifurcated end of the carrier receiver. As the shuttle travels further the open jaw 18 thereof close when the section of the receiver of reduced depth 33 is reached.

The extent of travel of the shuttle is determined by a stop at each end of the lay of the loom such as the stop 35 of the picker illustrated on the detail of the right hand side of the loom in Figure 9 of the drawings. A conventional shuttle brake to slow down the speed of the shuttle 15 as it enters the shuttle box is also provided such as the one 35a shown in dotted lines in Figure 9 of the drawings.

While the shuttle is at the left hand side of the loom, the carrier member 21, which has been deposited in the bifurcated end of the carrier receiver 25 with the tensioned filling thread 34 that it has just carried across the lay in front of the reed is caused to be carried forward by the lay 11 as the latter moves from the position illustrated in Figure 1 to that illustrated in Figure 2 to beat the pick from filling thread 34 just carried across into the cloth.

As the lay moves forward, the heddle on the left hand side of the loom through which filling thread 45 passes, drops towards the lay, and the carrier receiver 25 moves generally longitudinally of itself and towards the shed of the cloth being woven. As a result of the combined dropping of the filling thread 45 and movement of the carrier receiver 25, the exposed hook end of the hook 23 of the carrier member 21, engages with the filling thread 45. This engagement of the filling thread 45 is illustrated generally in Figures 10 and 11 of the drawings.

In the first motion the carrier receiver 25 moves toward the shed to substantially align the extended hooked end of the hook 23 with the filling thread 45, so that as the lay moves forward and the filling thread drops, the extended hooked end of the hook 23 engages with the filling thread 45 as illustrated in Figure 10.

When the lay is close to the forward extremity of its movement the carrier receiver 25 is caused to make a slight outward movement to pull the filling thread 45 slightly away from the shed as illustrated in Figure 11. The filling thread 45 is shown as it bends around a dent 46 of the reed 16. It should perhaps be mentioned that the forward motion of the lay herein referred to is the standard forward motion of the lay after the shuttle has travelled across the loom for the purpose of beating the pick of the filling thread just carried across.

When the lay is in, or close to its most forward position, a movement of the carrier receiver 25 longitudinally and towards the shed causes the projecting end of the hook or bar 23, of the carrier member 21 with the filling thread 45 to be depressed against the temple plate 48.

As it does this, it causes the bar 23 to slide within the body of the carrier member 21 and lock the filling thread 45 between the locking plate 24a and the bar 23 of the carrier member 21. At the same time the blade 24 of the carrier member 21 cuts the filling thread 45. With the securing and cutting of thread 45 filling thread 34 is released from the opposite hooked end of the bar 23 of the carrier member 21 as the latter hooked end emerges from the body of the carrier and a blast of air is caused to be emitted from the nozzles 48a of the air blast pipe 49 to blow both the free ends of the filling threads 34 and 45 into the shed to form a selvedge edge of the material being woven.

As the lay returns to its rearward position, the receiver 25 moves longitudinally of itself and away from the shed at a rate to take up the slack in the filling thread 45 between the spool (not shown but similar to 13) and the carrier member 21 due to the rearward movement of the lay to prevent the functioning of a standard stop motion, of the type that responds to a slack or broken thread, from stopping the loom from functioning. The operation of the receiver towards and away from the shed is described later in further detail.

As the lay moves rearwardly with the filling thread 45 secured in the forward end of the carrier member 21 the shed opens and the pick motion of the loom, which is not illustrated in these drawings, causes the shuttle 15 to travel to the right hand side of the loom and carry with it the carrier with a thread 45 from its spool. The timing of the opening of the shed for the passage of the shuttle varies according to the cloth desired as is well known in the art.

As the longitudinally extending channel 15a of the shuttle passes over the free end of the carrier receiver member 25 at the left hand side of the loom, and as the shuttle travels from left to right the grippers thereof are caused to open, engage the carrier member 21, close on the member 21 and then take it from receiver 25 at the left hand side of the loom and deposit it as previously explained in the receiver at the right hand side of the loom. As the shuttle travels to the right hand side of the loom filling thread 45 is tensioned and receiver 25, which is now empty returns to its normal position ready to receive the carrier on its subsequent return from the right hand side of the loom.

At the right hand side of the loom the same sequence of operation is repeated, that is while the pick of filling thread 45 is beaten into the cloth the filling thread 34 from the spool 13 that extends through the heddle 14 is caused to drop towards the lay as the carrier receiver 25 is carried forward by the lay whereby filling thread 34 is picked up by the extending free end of bar 23 of the carrier member 21. The filling thread 34 is then locked in the carrier member 21, cut off and the filling thread 45 released and the free ends of both filling threads are blown into the selvedge edge. Clearance between the side of the bifurcated end of the receiving member and the carrier is of course provided to permit the free blowing in of the thread 34 after its release.

The pick from filling thread 45 is of course beat by the reed as the lay moves forward.

Before the carrier member 21 reaches the right hand side of the loom, the heddle 14 through which the filling thread 34 passes is lifted to raise the filling thread 34 above the lay so that it is positioned to be dropped into the extended hooked end of the bar of the carrier during the forward movement of the lay ready for the next succeeding pick from the thread 34 as explained above.

The movement of the receiver 25 longitudinally of itself and inwardly and outwardly of the shed and the operation of the air blast nozzles 49 are controlled by the cam mechanism generally indicated by the numeral 26 in Figures 2, 8 and 9.

The receiver control cam 74 and the air blast control cam 75 are mounted on the ends of shaft 76 which extends

the entire length of the loom. It will be appreciated that the cam mechanisms on both ends of the loom are similar and that they differ only in their operating phases, the arrangement of the receiver control cam 74 to the air blast control cam 75 being the same and the two cam mechanisms operating conversely of each other. Each end of the shaft 76 on which a set of cams is mounted is journaled to the frame of the loom as at 77. An actuating arm 78 is pivotally mounted on the frame of the loom as at 79 and its free end 80 is connected to the link chain 81 as at 80a. A cam co-operating roller 78a is fixedly mounted with respect to the actuating arm 78 as at 78b. The roller 78a is urged into contact with the surface of receiver cam 74 by the spring loaded actuating means 25a located on the end of the lay through the link chain 81 which is attached to one side of the receiver mounting means 82. Figure 9c shows the connections of chain 81 to the receiver. A threaded shank 81a on the end of chain 81 extends through an oversize hole in lug 81b on the receiver and has a nut on its free end that bears against spring 81c. The purpose of the spring is to provide a cushioning effect for the impact of the carrier and the receiver. Alternative to the spring 81c one might provide a resilient rubber cushion for the carrier in the end of the receiver. The link chain 83 is attached to the opposite side of the receiver mounting as at 82a and link chain 83 is in turn attached to the spring loaded actuating means 25a; the spring loaded actuating means 25a providing the tension necessary to urge roller 78a against the surface of the receiver cam 74 previously mentioned. The receiver mounting means 82 is slidably mounted on the longitudinally extending guide rod 82b which acts as a means for maintaining the receiver 25 in alignment during the movement of the receiver by the cam mechanism 26.

The blast of air through nozzles 49 which blows the free ends of the filler thread into the open shed to form a selvedge edge of the fabric is supplied to the nozzles through hoses 84a and is controlled by a plunger 84 that operates a supply valve. Plunger 84 is cyclically depressed by cam 75 which is mounted on shaft 76.

Shaft 76 is chain driven through sprockets from the shaft (not shown) which operates the heddle drive means.

Cam 74 controls the movement of the receiver inwardly and outwardly of the shed. In operation the receiver cam 74 begins its cycle of movement at the point A on the cam and continues to turn clockwise as indicated by the arrows. The cam surface at point B causes the receiver to move slowly toward the shed so that the extended hooked end of the carrier can pick up a filling, move away from the shed, and then move abruptly towards the shed to cause the extended end of the carrier to engage with the temple plate as explained above to fix one end of a new filling in the carrier and release the end of a filling previously retained in the carrier. The cam continues its cycle in spring urged engagement with the roller 78a from the spring loaded actuating means 25a. The receiver begins its outward movement near the point C on the cam. An irregularity at point D on air blast cam 75 depresses plunger 84 as the carrier moves back to release the air blast from nozzles 49 and blow the released and cut filler thread ends into the selvedge edge of the woven material as described above. At point E on the receiver cam 74 the receiver 25 is at its outermost position from the shed. The shuttle 15 has by this time been fired to the right hand side of the lay and the receiver 25 then again moves towards the shed to assume its normal position as the receiver cam approaches the point F in the cycle. The cam surface holds the receiver 25 stationary at this normal position until the commencement of a new cycle of operation.

The operation and drive means for the warp thread heddles is well known in the art and it is therefore thought unnecessary to provide a detailed description of their

operation. The filling thread heddles 14 utilize the aforementioned warp heddle drive means as their operative source. The filling thread heddles 14 are spring biased from their lower ends as at 86 and 86a, similar to the warp thread heddle frames. The upper ends of the filling thread heddles are attached to actuating lines 87 and 87a which turn on pulleys 88, 89 and 90, the lines 87 and 87a terminating and being attached to the arm portions of reciprocating levels 91 and 92. The heddle actuating mechanism being generally referred to by the numeral 93.

In Figure 9b the manner in which the receiver 25 is slidably mounted on the lay is illustrated. The receiver is attached by means of the bolt 100 to the bottom of member 82 which is slidably mounted on the rod 82b, and which further has an arm 103 that rests on the longitudinally extending surface 104 of the lay. The chain 83 connects with one side of member 82 and the chain 81 connects with the opposite side whereby it is reciprocated by means of the operation of cam 74 and spring loaded spool 25a the coil spring of which 25b is illustrated in Figure 9b.

In Figures 14 to 39 of the drawings, I illustrate a shuttle loom having conventional means for imparting reciprocating motion to the lay, conventional means for driving the shuttle across the lay and conventional means for achieving warp thread feed. The loom is novel in respect of the filling thread feed and the means for forming the selvedge edge.

The lay, generally indicated by the numeral 500, is reciprocated between a forward position, illustrated in solid lines in Figure 16 of the drawings, and a rearward position illustrated in dotted lines in Figure 16, in the usual manner by the crank arm 502 as the main drive shaft 504 of the loom turns.

Warp threads, indicated by the numeral 506, are fed from the beam 508 at the back of the loom, through the drop wires 510 of a conventional electrically operated warp thread stop mechanism, through the warp thread heddles 512, and through the dents of the packing reed 514 to the cloth 516, in the standard manner that is well known in the art.

The warp thread heddles 512 are mounted in frames 513 in the usual way and are operated by jacks 520, which are in turn controlled by the pattern chain generally indicated by the numeral 522, to form the warp threads into sheds for the passage of the shuttle. The creation of the shed for the passage of the shuttle is well known in the weaving art and since it does not form a part of this invention detailed reference to it will not be made.

In the loom illustrated, a shuttle is driven across the lay 500 through the shed of warp threads in use by means of the conventional picker sticks 524 and 526. Picker stick 524, which is the same as picker stick 526, connects with a picker 528 that slides on a rod 530 mounted on the back of the right shuttle box 532 and enters the box 532 through a slot (not illustrated) to percussively engage the shuttle, as will be referred to again later. Since the action of driving a shuttle back and forth across the raceway of the lay 500 in front of the dents of the packing reed 514 by means of picker sticks is well known in the art, detailed reference will not be made to it. The shuttle boxes are each provided, according to well known loom practice, with brakes such as the one 540 on the right hand shuttle box 532. It will be noted that brake 540 is spring urged by means of springs 542 towards the back wall of the box and it is designed to break the speed of the shuttle as it lands in the box at the end of the raceway 534 of the lay 500. This is standard practice and brake design varies within the art. Detailed reference to it will, therefore, not be made.

According to one feature of my invention, the filling threads are retained in a carrier as the shuttle travels through the shed of the warp threads to transfer the carrier between receivers adjacent each end of the lay.

Means are provided at each end of the lay for fixing a filling thread to be incorporated into cloth being woven in the retaining means of the carrier when it is in the receivers. Means are also provided for releasing filling threads from the carrier when it is in the receivers after they have been carried across the lay.

In the drawings, the numeral 544 generally indicates a carrier for the filling threads and in Figure 19 it is illustrated between the grippers 548 and 552 of the shuttle 554. In use, as will be described later, the grippers 548 and 552 operate to transfer the carrier between receivers that are mounted adjacent each end of the lay such as the one 556 at the right hand side of the lay. The receiver 557 at the left hand side of the lay is, of course, similar. The receivers will be referred to in greater detail later.

The carrier 544 has means for retaining a filling thread when fixed therein whereby it carries the thread across the raceway of the lay as it in turn is gripped by the grippers of the shuttle and carried across the lay. The retaining means includes a sliding bar 560 having a hook formed adjacent each end thereof that is adapted to slide within a through slot 562 in the body of the carrier 544. The bar 560 has a length such that one hooked end thereof extends from the slot 562, the other being substantially within the slot as will be apparent from Figures 28 to 31 inclusive. The manner of mounting the sliding bar is most apparent from Figures 22 to 24 of the drawings. Bar 560 slides between a blade 563 that lies against the side of slot 562 in the body of the carrier 544 and a shoe 564 that is retained by a spring urged against the bar by a spring 566. Shoe 564 has a ball bearing 568 mounted therein that co-operates with the holes 570 and 572 in the bar 560, to locate the bar within the slot 562 with either one of the hooked ends of the bar extending from the slot. Shoe 564 is made from a somewhat resilient material such as nylon and the holding force of the ball mounted therein is designed such that it can be overcome to permit the bar to slide in use. In use as will be described later, a filling thread is dropped into the exposed hooked end of bar 560. The bar is then slid within the body of the carrier to locate the end within which a thread has been dropped within the slot and expose the other hooked end. As it is so slid, the thread just placed in the exposed hooked end is drawn into the slot, first between the shoe and the bar since the shoe is longer than the blade 563. As the said thread is drawn further into the slot by the bar, it engages with a cutting edge of the blade 563 and is severed by the knife action of the cutting blade and the hook of the bar. One of the free ends so formed is retained within the slot between the shoe and the bar 560. The other free end is released from the bar and retained in place by the temple spring until returned into the selvedge as will be described fully later. As a filling yarn is fixed in one end of the carrier as just described, a different filling yarn retained between the shoe 564 and the bar 560 at the other end is released as a hooked end of the bar is caused to extend from the latter end of the carrier.

It will be noted that the top and bottom of the carrier 544 are rounded and complementary to the gripping surfaces of the grippers 548 and 552 in the shuttle. One side of the carrier 544 is formed with a scallop as at 574, for cooperating with a prong of receiver members 556 and 557. The opposite side of the carrier is formed with a longitudinally extending channel 576 that extends for the full length thereof to protect and provide clearance for the yarn held in the carrier so that it can be freed when the carrier is in the receiver as will be described later. It will be noted that spring member 566 is formed with a boss 578 that imbeds in a round hole 580 through a side of the body of the carrier to positively locate it within the hole. Blade 563 is formed with a boss 579 that also co-operates with a hole in the carrier to locate it in a similar manner. It will be apparent that

when the spring 566 is stressed as indicated in Figure 24 that boss 578 will seat in the hole 580 to secure the resilient shoe 564 with which it co-operates against displacement from the through slot 562 in the body of the carrier and that boss 578 will seat in its respective hole in the carrier body. The limits of travel of the bar 560 are, as has previously been referred to, determined by the co-operation of the holes 570 and 572 formed in the bar with the ball bearing 568 carried by the resilient shoe 564.

The shuttle 554 has as indicated above, means for transferring the carrier 544 between the two receivers and to this end is formed with a longitudinally extending channel 582 within which is mounted the pair of grippers 548 and 552. Grippers 548 and 552 are preferably made of a hard fibrous material and are mounted on spring members 584 and 586 respectively that are in turn rigidly mounted on the walls of the channel 582, as at 588 and 590, and as at 592 and 594 respectively. The grippers 548 and 552 are mounted on their respective springs by means of screws 596 and 598 which pass through the spring members and threadedly engage with retaining plates 600 and 602 respectively at the back thereof. The plates 600 and 602 limit the travel of their respective grippers towards the sides of the channel 582 while the pins 604 and 606 carried by plates 600 and 602 respectively, limit the travel of the two grippers towards each other by their engagement with the side edges of plate 608. Plate 608 is bolted to the channel 582 by means of bolts 609.

A second channel 610 is provided on the opposite side of the shuttle. This latter channel co-operates with a rib at the entrance to the shuttle boxes 532 and 533 and functions as a guide for the shuttle as it enters the boxes as will be explained later. In addition the tip of the shuttle has a sloped surface, as at 612, that co-operates with the receiver to align the latter to receive the carrier member as will be explained later. Grippers 548 and 552 are normally urged by the force of the springs 584 and 586 respectively to a closed position to grip the carrier member 544 as illustrated in Figures 19, 21 and 22. On encounter with the receiver, however, the carrier co-operatively engages with the receiver through the action of the shuttle and the grippers release their grip on the carrier as will be explained later.

I might add that in Figure 19 the view of the shuttle is one that would be obtained on looking at the shuttle in operation from the back of the loom, that is, the side of the shuttle seen in Figure 19 abuts the dents of the packing reed 514 in use.

As indicated above, I provide receivers 556 and 557 adjacent each end of the raceway 534 of the lay 500.

As best seen in Figures 28, 33 and 34, the receiver at the right hand side of the lay generally indicated by the numeral 556 which is similar to the receiver at the left hand side, comprises a bar 614 bifurcated at one end as at 616 and pivotally mounted near its other end on a lug 618 that extends from rack 620 to overlay the raceway 534 of the lay 500. Rack 620 is free to slide longitudinally of the lay within the gear box 622 which is rigidly mounted on the lay. Lug 618 of rack 620 extends through a longitudinally extending slot in gear box 622 whereby bar 614 of the receiver 556 is carried longitudinally of the lay with the rack. The manner in which the rack is actuated longitudinally within its gear box will be referred to later.

The bifurcated end 616 of receiver 556 has one of its inner vertical walls 624 formed with a convex outline in vertical cross section to be complementary to the concave of the scalloped wall 574 of the carrier 544 and its opposite inner vertical wall 626 spaced therefrom to receive and retain the carrier between the two, as indicated in Figure 20, when the carrier is carried into contact therewith by the shuttle. In this latter connection, it will be noted that the bar 614 of receiver 556 over-

lays the raceway of the lay with its longitudinal axis aligned with the groove 582 of the shuttle, the groove 582 being large enough that it can pass over the bar 614 as the shuttle is driven back and forth across the raceway of the lay by the pickers. As the shuttle passes the receiver on its way into the box the grippers 548 and 552 thereof carry the carrier 544 into co-operative engagement with the bifurcated end of the receiver whereby the carrier only is arrested in the receiver in the position shown in Figures 29 and 30. As the shuttle continues on its way into the box the spring loaded grippers slip over the carrier 544 until their ends clear the carrier and their grip is released.

It will be appreciated that the shuttle does not normally follow exactly the same path across the raceway 534 of the lay 500 each time and means are provided for aligning the shuttle with the receiver and for aligning the receiver with the shuttle so that the carrier will enter the bifurcated end of the receiver accurately.

The shuttle is aligned in part by means of a longitudinally extending rib 627 on the vertical wall 628 of a housing 630 mounted on the lay 500 (see Figure 25) that co-operates with the longitudinally extending groove 610 in the shuttle. Housing 630 has been removed from the lay of the loom in Figure 26 to more clearly illustrate the receiver. It is, however, bolted to the lug 632.

Means are also provided for causing the bar 614 of the receiver 556 to accurately align with the carrier retained in the grippers of the travelling shuttle as the shuttle enters the shuttle box. In this latter connection it will be noted that a spring 634, having one end in an appropriate hole formed in the rack 620 and its other end in an appropriate hole in the bar 614 of the receiver is compressed to normally urge the bifurcated end of the bar away from the gear box to the solid line position of Figure 34. It will be recalled that bar 614 is pivotally mounted on lug 618. The contact of the bar 614 with the gear box is the stop means to limit the outward position of bar 614.

The bar 614 can be deflected against the pressure of spring 634 to assume the dotted line position in Figure 34 if necessary.

As the shuttle first approaches a receiver, the curved surface 612 of the tip thereof engages with the curved portion 636 of the bifurcated end of the bar 614 to move it inwardly from the solid line position towards the dotted line position a sufficient amount to accurately align the receiver in its plane of permitted movement with the carrier carried in the grippers of the shuttle, so that the carrier will enter into the bifurcated end of the receiver.

The groove 610 and its co-operating rib 627 tend to steady the shuttle in a direction at right angles to the raceway of the lay.

As the shuttle leaves a shuttle box at the end of the lay on its way to the other side of the loom the gripper springs 584 and 586 yield upon encounter with the carrier in the receiver and the grippers open to engage with and retain the carrier 544 between their ends and carry it to a receiver at the other side of the loom.

When the carrier 544 is first transferred to a bifurcated end of a receiver, it retains the free end of a filling yarn in the end thereof that enters into the receiver first and an empty hook of the sliding bar 560 extends from its other end and beyond the receiver bar as indicated in Figures 30 and 31. The filling yarn secured to its first mentioned end has been carried across the lay through a shed of warp threads from a spool supply behind the lay at the opposite side of the loom. As will be described later, a pick from the filling thread just mentioned is beaten into the cloth and it is either cut free or released from the carrier and another filling thread from a supply at the side of the loom where the carrier is in

the receiver is fixed in the carrier so that it can be carried across the lay through an open shed of warp threads to the receiver at the opposite side of the loom. These operations will be described in greater detail later.

In Figure 16 the supply of filling thread 644 is shown as extending from spool 646, through appropriate tensioning devices, through a drop wire 510 of an electrically operated thread stop mechanism, through heddle 650, through the reed 514 to the selvedge edge of the cloth and then across the cloth to the opposite side thereof as will be apparent later. It will be noted that the heddle 650 is raised in readiness to drop its filling thread into the hooked end of the carrier bar as will be referred to again later.

A filling thread 642 emanates from a spool similar to the one 646 but on the left hand side of the loom. It is fed in a similar manner to the thread 644 but the arrangement is not specifically illustrated.

An alternative filling thread supply is indicated in the Figure 18. In the latter case, the filling 644 extends from a spool 646A through a tensioning device 646B through a flexible slack adjusting cane 646C and through a drop wire 510 of a stop mechanism as before. Picks from the filling threads 642 and 644 are incorporated into the cloth as the shuttle transfers the carrier between the receivers as will be described later.

When the carrier 544 is first transferred to, for example, the left hand side of the loom (see Fig. 35), it retains the free end of a filler yarn 644 at its left end between the bar 560 and the resilient shoe 564. Filling 30 thread 644 extends from the left end of the carrier, along the groove 576 therein, through the shed to the right hand side of the loom, and back between the dents of the reed, to the supply spool 646 as explained above.

At the same time, the filling thread 642 extends from a spool in a similar manner to thread 644 to the selvedge edge of the material at the left hand side of the loom from which it extends across the cloth to the right selvedge edge of the cloth. It has been raised by its heddle above the height of receiver 544.

I provide a means for fixing the filling thread 642, which as viewed in Figure 35 has been caused to overlay the lay, into the right end of the carrier 544 so that a pick therefrom can be woven into the cloth by the next succeeding pass of the shuttle across the lay, and means for releasing the free end of the filling yarn 644 that has just been carried across the lay by the next preceding pass of the shuttle across the lay.

It will be apparent that when the filling yarn 642 is fixed into the carrier it must be severed and an end will of necessity be left free which extends from the selvedge edge of the material. There will also be a free end to the filling yarn 644 after it has been released from the carrier adjacent the selvedge edge of the material. As will be referred to later I preferably provide means for incorporating these free ends into the selvedge edge of the material.

In the weaving of a typical woollen worsted fabric, the lay 500 would be midway between its rearmost and foremost positions and moving forward when the carrier 544 arrives in the receiver 557 as illustrated in Figure 35. The means that I employ for fixing the filling yarn 642 in the carrier 544 so that a pick therefrom can be carried across to the opposite side of the loom, includes a means for moving the receiver 557 longitudinally of itself and to the right and means for simultaneously dropping the filler yarn heddle through which the thread 642 passes so that the thread 642 drops into the extended hooked right end of the bar 560 as viewed in Figure 36.

As the lay continues in its forward movement the receiver 557 moves back to the left and longitudinally of itself again so that the free end of the hooked member 560 lies to the left of the side of the temple 800. When the lay approaches its most forward position, the receiver 557 again moves longitudinally of itself to the right to

cause the free end of the bar 560 to engage with the side of the temple 800 and to slide the bar between the cutting blade 563 and the resilient shoe 564. This secures filling 642 in the carrier, cuts filling 642 to free the part that extends from the cloth and releases filling 644 from the carrier.

In Figures 29 to 32, I have illustrated the two positions of the cutting bar with respect to the carrier. They illustrate the carrier in the receiver at the right hand side of the lay but it will be appreciated that the receivers at the two sides are the same with the exception of hand. The carrier is shown as it is received in the receiver in Figures 31 and 32 with a filling thread 642 in this case secured to its right hand end. As a result of its being forced into contact with the side of a temple as just described in connection with the left side of the loom, the bar slides from the position illustrated in Figures 31 and 32 to that illustrated in Figures 29 and 30, the receiver 557 being formed with the slot 561 to accommodate the end of the double hooked bar 560.

As the extended hooked end of the double hooked bar 560 is pushed into the body of the carrier 544, the thread in the extended hooked end of the bar 560 is first gripped between the hooked member and the resilient shoe 564 and then it is cut by the cutting action of the hooked member and the cutting blade 563. Thus the supply free end of the filling yarn is fixed in the retaining shoe and bar of the carrier 544 and the other end resulting from the cutting is free adjacent the selvedge edge.

It will be apparent that as the double hooked bar 560 has its extended end forced into the carrier member 544 from its position as viewed in Figure 37 that the free end of filling thread 644 that is retained in the left hand end of the carrier member between the hooked member and the resilient shoe thereof will be released because the hook at the left hand end of the carrier member will extend from the body of the carrier member. Thus the free end of the filling thread 644 that has been carried across the loom on the next preceding pass of the shuttle 40 is released from the carrier.

It may be desirable to leave the end of the filling yarn 642 that extends from the selvedge edge, and the end of filler yarn 644 that has just been released, free in order to form a fringe on the edge of the fabric. However, I 45 will be describing means for incorporating the free ends into the selvedge edge of the material in a particularly neat and advantageous manner.

If the free ends of the fillings are to be incorporated into a selvedge edge, an air blast is provided for blowing 50 them into an open shed and for maintaining them there until the shed closes to lock them in the edge of the cloth. In a preferred method of forming the selvedge edge, the pick of filling 644 carried through the shed by the carrier is cut adjacent to but short of the edge of the fabric 55 and the small piece thereof between the place of cutting and the carrier is retained in the carrier for removal on release therefrom by a suction means as will be explained later. The cloth free end of the filling thread 642 of which a pick is about to be inserted in the cloth and 60 which is cut by the action of the sliding bar and the carrier described above is preferably secured in a retaining means prior to the said cutting, and released therefrom at any appropriate time for blowing into the open shed by an air blast.

In this latter connection, that is the retention of the cloth free end of the filling 642 prior to its blowing into the selvedge edge, I provide a plate 802 on the forward end of the temple 800 that is formed with a slit as at 65 803. A spring 804 is rigidly mounted to press against the upper edge of the slit 803 as shown in Figure 38. Slit 803 is located and the forward end of spring 804 is curved so that as the lay moves forward prior to the severing of the filling thread by the carrier bar, the said 70 filling thread enters between the upper edge of the slot 75 and the lower edge of the slit 803.

and the spring 804 and is retained thereby for subsequent blowing into the selvedge edge.

An air nozzle 808 has a stem with an air outlet 810 and a V-shaped end 812. The nozzle is slidably mounted within the temple 800 so that the stem thereof moves longitudinally of itself and is in abutting relation with the plate 802. In its normal position illustrated in Figures 36 and 38 its stem is co-extensive with the slit and the V-shaped end thereof extends across the mouth of the slit 803. Tension spring 814 which extends between the nozzle and the temple maintains the nozzle in its aforesaid normal position.

The forward end of the lay engages with a pin 815 on the nozzle, as it moves forward to pack the pick whereby to slide the nozzle rearwardly within its slideable mounting within the temple against the tension of spring 814 and move the stem thereof longitudinally of itself and rearwardly of the slit. Thus a filling 642 hooked in the extended hooked end of the carrier and carried forward by the lay as the latter moves forward can enter the slit 803 as illustrated in Figure 37 to be retained between the upper edge thereof and the spring 804.

As the lay moves further forward, the filling thread thus retained in the slot is severed due to the co-action of the carrier and the temple as explained above. It will be apparent that the fabric free end of the filling 642 is retained in the slot 803 at severance.

As the lay moves rearwardly from its foremost position and after the filling yarn 642 has been severed and the free end thereof is retained between the spring 804 and the edge 803 of the slot, the lay disengages from the pin 815 and tension spring 814 causes the nozzle 808 to slide forward within the temple whereby the V-shaped end 812 of the stem of the nozzle engages with and ejects the free end of the thread 642 from the slot 803. Also as the lay moves back and the shed begins to open, means are provided for causing a blast of air from the opening 810 of the nozzle to blow the free end of the filling thread into the opening shed to form a selvedge edge. The air from the nozzle begins before the V-shaped end of the nozzle ejects the thread and is continued until all danger of the free end of the thread 642 from coming out of the shed has passed.

The above described method of providing a means for holding the free end of the filling yarn severed prior to blowing it into the selvedge edge is preferred. However, one might well provide any simple air blast means for blowing the free ends of the filling yarn into the selvedge edge.

I have only specifically thus far mentioned the blowing in of the free end of the yarn 642 at the left hand side of the cloth. It will be apparent that there is also a free end of the yarn 644 freed from the carrier to be blown into the selvedge edge or otherwise disposed of if a neat edge is required. In the case of the yarn 644 I prefer to cut it at a predetermined distance from the edge of the cloth and then to remove the short length of filling yarn 644 thereby created that extends between the place of cutting and the end in the carrier.

In Figures 25, 35 and 36 I have indicated a knife blade 820 that is operative to cut the yarn 644 after the shed has closed thereon to hold it during the forward motion of the lay and after the carrier has been received in the receiver at the left hand side of the loom as indicated in Figures 35 to 37. The blade 820 co-operates with a dent of the packing reed to cut the thread 644 close to the edge of the material and approximately at a distance from the edge equal to the length of the free end of thread 642 that has to be turned into the selvedge edge whereby when the free end of a yarn 642 is blown into the open shed as described above its free end will extend to the free end of the yarn 644 where it is cut. This method makes an exceptionally neat and tidy selvedge edge. The

cutting blade 820 co-operates with a dent of the packing reed 514 to perform the cutting operation.

In a typical loom operation cutting could take place just before the lay reaches its front center position when the carrier 544 is in the receiver. By this time the reed 5 has advanced and the shed has closed upon the pick of filling laid into the fabric by the last preceding pass of the shuttle and it will not move after cutting whereby its tension is maintained.

10 When the blade 820 cuts a filling 644 as described, a small piece thereof is retained in the carrier. As filling yarn 642 is fixed into the carrier, this small piece is released. I provide a suction tube 821 having an opening 15 appropriately placed near the end of the receiver to remove these small pieces as they are freed from the carrier.

After the thread 644 has been released from the carrier the thread 642 secured into the carrier, and the shed is opened sufficiently the shuttle is operated to carry the 20 carrier across to the right hand side of the loom where the same operations take place.

I have referred to the means for fixing filling threads into the carrier and for releasing filling threads from the carrier and for incorporating the free ends of filling 25 ends into the selvedge edge, without describing all details of those means.

The means for fixing a filling yarn into the carrier includes the heddles referred to and means for raising and lowering them, means for moving the receivers longitudinally along themselves, and the side of the temple. 30 It will be appreciated that the means are the same at each side of the loom.

In Figures 27, 33 and 34 I have illustrated the means for moving the receiver longitudinally of itself at the 35 right hand side of the loom.

The bar 614 of the receiver is reciprocated in use by the action of cam 656 that is mounted on shaft 658. Shaft 658 is suitably driven from the main drive shaft of the loom to turn in a counterclockwise direction as 40 viewed in Figure 26 at one-half of the speed of the main drive shaft of the loom. A cam follower 660 carried by the arm 662, co-operates with cam 656. Arm 662 is pivotally mounted to the frame of the loom at one end as at 664 and biased at its other end by a spring 666 to 45 cause the cam follower 660 to engage with the cam 656. A connecting rod 668 pivotally connects with arm 662 as at 670 and with arm 672 as at 674. Arm 672 rigidly connects with the shaft 676 which is journaled between its ends in the gear box 622. Pinion 677 is connected 50 to the other end of shaft 676. It will be apparent that as the cam follower 660 follows the depressions of cam 656 that the rack and hence the bar 614 of the receiver will move longitudinally of the lay of the loom through the connections just previously described.

55 The bar 614 of the receiver is in its normal position that is the one it assumes when it receives the carrier, when the cam follower 660 is on the rounded portion 678 of the cam 656. As the cam rotates in a counterclockwise direction, the cam follower will enter upon 60 the depression 680. It will be apparent that this will cause the bar of the receiver to move forward or to the left in Figure 26. As rotation of the cam 656 continues the cam follower will rise to the point 682 on the cam which will cause the bar of the receiver to move back or to the right as viewed in Figure 26. When the depression 684 is encountered by the cam follower, the bar of the receiver will move abruptly forward or to the left as viewed in Figure 26 a distance limited by contact of the end 636 thereof with the side of the temple, 65 and will then subsequently move slowly back and to the right to achieve the normal position again at point 686. I have described the operation of the receiver at the right hand side of the loom. It will be appreciated that the operation is the same at the left hand side of the loom.

In Figure 14 I have illustrated the manner of operating the filling thread heddles. The heddle at the right hand side of the loom has been numbered 650. The heddle at the left hand side of the loom is the same and in Figure 14 I will refer to the heddle at the left hand side of the loom by the numeral 651 to distinguish it from the heddle at the right hand side.

Heddle 650 connects at one end with a spring 900 and at its other end with the cord 902. Spring 900 is in tension and connects at its opposite end with the frame of the loom as at 904. Cord 902 extends over pulley 906 and pulley 907 to the arm 910 and connects therewith as at 912. A tension spring 914 connects with the free end of arm 910 as at 916 and with the frame of the loom as at 919. Arm 910 is pivotally mounted to the frame of the loom. A cord 920 joins the arm 910 to a jack 922.

Heddle 651 is also connected at one end to a tension spring 924 which in turn connects with the frame of the loom as at 926. The opposite end of the heddle 651 connects with a cord 928 which passes over pulleys 930 and 932 to connect with the pivotally mounted arm 910 as at 934.

In the position illustrated, the heddle 650 is in a raised position and the heddle 651 is in a lowered position. The lowered position being the one it travels to as it presents a filling thread to the extended hooked end of the carrier bar. The raised position is the one that the heddle assume in readiness to drop its filling thread into the extended hooked end of the carrier as described above. It will be apparent that the position of both heddles is governed by the position of the arm 910 and the tension springs 900 and 924. For example when the arm 910 is in the position illustrated the spring 924 draws the heddle 651 to its lowered position and heddle 650 is lifted to its raised position against the tension of spring 900.

By appropriate operation of the jack 922 the arm 910 can be moved to the right against the tension of spring 914 to assume a position similar, but in front of, the position of the arm illustrated by the numeral 940. This movement will permit the heddle 650 to drop under the action of spring 900 to assume a position similar to the illustrated position of the heddle 651 in height. At the same time heddle 651 will be caused to raise as the spring 924 is tensioned to assume a position similar to the position illustrated for heddle 650. When jack 922 is moved again to the left, arm 910 will return to the position illustrated under action of spring 914 and the heddles will assume the positions shown as a result of action of springs 900 and 924. Other means of course could be used for raising and lowering the heddles.

Arm 940 has heddles similar to the heddles 650 and 651 similarly connected to it. These heddles are behind the heddles 650 and 651 and can be used to supply additional filling yarns. It will be appreciated that in this description I have referred to a fabric or cloth having one filling thread supplied from each side of the loom but it will be apparent that any number of filling threads could be supplied providing a heddle is provided for each filling thread together with means for raising it and lowering it as described for feeding to the carrier.

The operation of the jack 922 can be conventional. I have successfully operated it by the conventional pattern chain appropriately set to activate the desired jacks to control the filler heddles. A person skilled in the art would be able to arrange the operation of the jack to raise and lower the heddles 650 and 651 as required for the application described.

The means for forming the selvedge edge mentioned above includes the cutting blade 820 that, as indicated above, operates to cut a filling thread carried across the loom after the carrier has been deposited in the receiver and after the shed has closed sufficiently to hold it against movement after cutting. Blade 820 is cam operated from the drive shaft of the loom and in Figure 25 I illustrate its

manner of mounting and operation at the right hand side of the loom.

I am using the same numeral for the blade on both sides of the loom. Blade 820 as seen in Figure 25 is carried by a bar 850 that is pivotally mounted in the bracket 852 as at 854. Bracket 852 is rigidly mounted on the top bar of the packing reed of the loom by means of a bolt as at 856 to normally dispose the blade 820 behind the dents of the packing reed as best seen in Figure 35 which it will be appreciated is the view of the left hand side of the loom.

The normal position of the blade 820 just referred to is the one that is assumed when the cam follower 858 which controls it rides on the round portion of its control cam 860. Cam follower 858 is mounted on the arm 862 that is pivotally mounted on the frame of the loom as at 864. At its other free end the arm 862 connects with operating rod 866 as at 868. Rod 866 at its other end pivotally connects with the link 870. Link 870 also pivotally connects with the bar 850. A tension spring 872 connects between the frame of the loom and the end of the arm 862 as illustrated to cause the cam follower 858 to follow the cam 860. It will be noted that cam 860 is round with the exception of a single depression 878. As the shaft 658 rotates the cam follower 858 rides into and out of the depression 878. As it does so it will be apparent the linkages just described will function to cause the blade 820 carried by the pivotally mounted bar 850 to rise and fall. As indicated above the blade in its normal position is just behind a dent of the packing reed. As it rises it passes through to the front of the packing reed to slip over and overlie a filling yarn just brought across the loom. The blade in this position is illustrated in Figure 36 of the drawings. Again it will be appreciated that this view is at the left hand side of the loom. As the blade falls to again assume its normal position behind the reed plate it cuts the filling yarn by reason of co-action with a dent of the reed.

The temple has as indicated a nozzle 808 slidably mounted therein and is spring urged to the position illustrated in Figures 36 and 35 by means of the tension spring 814. The air supply previously referred to for the nozzle is through the tube 890 and is appropriately controlled by means of the cam 892 in conjunction with the cam follower 894 to operate the control valve 896. It will be apparent that each time the cam 892 strikes the cam follower 894 as the shaft 658 rotates the follower 894 is actuated to turn the air blast on. The duration of the air blast can be of course controlled by the length of contact between cam 892 and cam follower 894. The temples at both sides of the loom are identical.

I will describe the method of weaving cloth according to my invention with the loom that I have illustrated in Figures 14 to 39 of the drawings. To do this I will refer to Figure 39 which is a schematic illustration of the cloth 516 when the loom is in the position of Figure 36. The filling 644 extends from its supply spool 646 and enters the cloth 516 adjacent the right selvedge edge thereof from which it extends across the cloth. Its free end is still retained in the carrier 544. Filling 644 passes through the tensioning devices, the stop mechanism, heddle and reed as previously described.

Filling 642 likewise extends through tensioning devices, a stop mechanism, heddle and reed and enters left selvedge edge of the cloth from which it extends across the fabric to the opposite side thereof where it terminates just short of the edge as at 901. The portion thereof that extends across the fabric has been beaten into the cloth and now constitutes a pick.

The filling 644 just having been carried across the loom it is now desired to beat it into the cloth and to insert a new pick of the filler yarn 642 into the cloth. Therefore as the lay moves forward from the position of Figure 36 to beat a pick of filling 644 the shed of warp threads closes and the heddle for the filler 642 drops to

insert the thread 642 into the extended hooked end of the bar 560 as illustrated in Figure 36.

As the lay moves still further forward the cutting blade 820 in response to the operation of its cam 860 moves upwardly and the tensioned filling thread 644 slips over the sloped end thereof so that the cutting edge of the blade overlays the filling 644 (see Figure 25). As the lay moves further forward the cam 860 rotates further to cause the cutting blade to drop on the filling thread 644 and to sever this pick of filling thread 644 at 902 against a dent of the packing reed close to, but spaced inwardly from, the edge of the fabric 516. Prior to the cutting, the shed has sufficiently closed on the filling yarn 644 to hold it so that following cutting it will not move in the fabric.

As the lay moves still further forward the receiver in which the carrier 544 rests starts to move to the left and away from the shed to clear the side of the temple 800 and at the same time withdraws the free end of the short portion of filling 644 held in the carrier from the cloth. The receiver then begins to move to the right and towards the shed as the lay approaches its most forward position, and co-operates with the side of the temple to slide the cutting bar 560 to sever the yarn 642 adjacent the selvedge edge of the cloth. The actual severing preferably takes place when the lay is in its foremost position because at this point in the movement the lay temporarily stops prior to moving back and the friction between the end of the cutting bar and the temple is reduced.

It should perhaps be noted as the lay moves forward to its most forward position just referred to, that the filling yarn 642 is drawn between the upper edge of the slot 803 and the spring 804 for retention thereby, it being appreciated that the nozzle 808 is slid within its mounting in the temple 800 to free the slot for this purpose by reason of contact of the lay with the pin 815 of the nozzle. The nozzle is forced rearwardly against the tension of spring 814.

As filling thread 642 is cut in a manner just indicated, the supply free end is secured in the forward end of the carrier 544 and at the same time the short portion of the filling thread 644 that was secured into the left hand end of the carrier 544 is freed and is drawn away through the vacuum tube 821.

The free end of the filling thread 642 is retained by the slot 803 and spring 804 at a distance spaced from and to the left of the edge of the selvedge of the cloth.

As the lay moves back the shed begins to open and the air nozzle 808 begins to move forward under the tension of spring 814. As it does so, the V-shaped end 812 thereof forces the free end of yarn 642 retained thereby out of the slot. When the yarn is almost out of the slot a blast of air is emitted from the nozzle 810 through the valve 896 as controlled by its cam and cam follower 892 and 894 respectively. The blast of air forces the free end of the yarn 642 into the opening shed towards the free end of the yarn 644 where it was severed at 902. The points of severing 902 and 904 are preferably arranged so that two free ends are the same distance from the edge of the selvedge edge. The air blast is maintained for a period until the shed again closes to ensure that the blown in free end of filling 642 be held by the closed shed and will not come out of the fabric.

As the lay moves further back and the shed continues to open the shuttle is driven across the lay by the picker stick to pick up the carrier 544 and carry it with its contained filling thread 642 to a receiver at the right hand side of the loom. The carrier is received at the right hand side of the loom at substantially the same time in the loom cycle as it was received at the left hand side of the loom that is, as the lay is moving forward. The operation just described is repeated with the exception that in this case it is the thread 642 that is cut by the knife

and the thread 644 that is cut by the bar of the carrier. By repetition a fabric is woven.

I have described the method of weaving employing a single filling yarn at each side of the loom. It will be apparent to those skilled in the art that one could have many colours at each side of the loom provided each colour passed through a separate heddle from a separate supply spool or the like. Each colour would of course extend across the fabric and from one selvedge edge of the fabric to the supplies as indicated, and when it was desired to put in a filling yarn of a particular colour one would merely operate the appropriate heddle to drop the thread into the hooked end of the carrier.

Modifications in my invention as described in this application will be apparent to those skilled in the art. I have illustrated two looms according to my invention. It will be apparent that there are many other standard looms that differ in many respects to those illustrated that could also be changed to weave according to my invention. I might add that in the embodiment which I have illustrated in Figures 14 to 38, an electrically operated filling thread stop mechanism has been employed. One will appreciate that after a filling thread has been severed by the movement of the receiver against the temple and the lay begins to move rearwardly, that the filling thread will become slack and the electrically operated filling thread stop mechanism would normally function to stop the loom. To avoid this, I have provided a cam suitably formed and mounted on a drive shaft of the loom to shut off the electrically operated filling thread stop mechanism during the period that the filling thread is slack as the lay begins to move rearwardly after cutting the filling thread.

I have also found that the cane 646C illustrated in Figure 18 is effective to take up the slack in the filling as the lay moves rearwardly whereby to prevent unwarranted operation of the filling stop mechanism. As the thread is drawn from the supply spool 646 the cane 646C is moved against the loading of a spring at its base from the dotted line position to the solid line position. As the lay moves rearwardly the spring reasserts itself and takes up the required slack to prevent the stop mechanism from operating.

Further, when one makes a selvedge edge by cutting the picks short of but close to the edge of the material as described above and blowing another filling in towards it as described above, an uneven selvedge will result if a thick filling is employed because two fillings would be in one shed at the selvedge edge. This can be avoided by retaining the fabric free end of the filling that is blown into the selvedge edge until the carrier has been to the opposite side of the loom and returned, and then releasing the said fabric end of the filling and blowing it into the same shed as the thread just carried across and that is to be cut off close to but short of the edge of the material. In this way, both the end of the pick that is cut short of but close to the edge of the material and the end of the filling that is blown into the cloth are in the same shed. I provide a lock to maintain the nozzle in the position to which it is actuated by the forward motion of the lay that is cam released to permit the nozzle stem to eject the retained filling end from the slot when the carrier returns as just described. The lock release is not illustrated because it is thought that anyone skilled in the art would not have difficulty selecting an appropriate lock and a lock release operated by a cam driven by the loom drive.

I might also add that the vacuum supply that removes the small pieces of filling after cutting by the blade 820 should be turned off when not required to remove pieces of thread. Otherwise, a broken filler may enter whereby the broken filling would be maintained under tension and the stop mechanism of the loom would not work.

It will also be apparent that normal loom adjust-

ments can be made that may change the operation of the loom somewhat as is well known in the art.

What I claim as my invention is:

1. In a loom a lay, means for imparting reciprocating motion to said lay, means for achieving warp feed, a shuttle, means for driving said shuttle across said lay through the shed of warps, a reed, supply means for supplying at least one filling yarn adjacent each end of said lay, a carrier for filling yarns normally in said shuttle but being removable therefrom, a receiver for said carrier at each end of said lay for removing said carrier from said shuttle near the end of its flight in use, in either direction, means carried by said shuttle for permitting transfer of said carrier from one receiver to the other and vice versa as said shuttle is driven across the lay, said carrier having retaining means for a filling yarn, filling yarn fixing means for engagement with said carrier, means at each end of said lay, each operable when said carrier is at the one of said receivers at its respective end of said lay, for moving said filling yarn fixing means and carrier relatively to each other to cause inter engagement thereof whereby to operate said filling yarn retaining means to fix an end of a filling yarn supplied at its respective end of said lay in said retaining means of said carrier and to release an end of filling yarn from said retaining means supplied at the other end of said lay and carried through the shed by said carrier.

2. A loom as claimed in claim 1 in which said receivers comprise elongated bars having bifurcated ends, the bifurcated ends of said receivers being adapted to receive said carrier as it is transferred between said receivers by said means for permitting transfer of said carrier from one receiver to the other, said shuttle being formed with a channel extending longitudinally thereof, said means for permitting transfer of said carrier from one receiver to the other being mounted in said channel, said channel being adapted to pass over said receivers as said shuttle travels across said lay.

3. A loom as claimed in claim 1 in which said means for permitting transfer of said carrier from one receiver to the other comprises at least two grippers both resiliently mounted upon said shuttle and adapted to yield in gripping and releasing said carrier as it is transferred from one receiver to the other as aforesaid.

4. A loom as claimed in claim 1 in which said means for permitting transfer of said carrier from one receiver to the other comprises at least two grippers both resiliently mounted upon said shuttle and adapted to yield in gripping and releasing said carrier as it is transferred from one receiver to the other as aforesaid, and in which said receivers comprise elongated bars having bifurcated ends, the bifurcated ends of said receivers being adapted to receive said carrier as it is transferred between said receivers by said grippers, said shuttle being formed with a channel extending longitudinally thereof, said grippers being mounted in said channel, said channel being adapted to pass over said receivers as said shuttle travels across said lay.

5. A loom as claimed in claim 1 in which said means for permitting transfer of said carrier from one receiver to the other comprises at least two grippers both resiliently mounted upon said shuttle and adapted to yield in gripping and releasing said carrier as it is transferred from one receiver to the other as aforesaid and in which said filling yarn retaining means includes hooked means on said carrier for engaging a filling yarn as it extends from the selvage edge of cloth being woven to its respective supply means and means for severing a filling yarn engaged by said hooked means adjacent its point of engagement therewith to form a cloth free end.

6. A loom having in combination a lay, a reed, warp and filling yarn supplies, a shuttle, a yarn carrier adapted to be borne by the shuttle to pull a yarn across the lay, means to remove the carrier from the shuttle and re-

thread the carrier with yarn as the shuttle completes each traverse across the lay and then return said carrier to said shuttle as the shuttle begins each traverse across the lay, and at least two grippers both resiliently mounted upon said shuttle for transporting said carrier when borne by said shuttle.

7. A loom having in combination a lay, a reed, warp and filling yarn supplies, a shuttle, a yarn carrier adapted to be borne by the shuttle to pull a yarn across the lay, 10 means to remove the carrier from the shuttle and re-thread the carrier with yarn as the shuttle completes each traverse across the lay and then return said carrier to said shuttle as the shuttle begins each traverse across the lay, and heddles and pattern mechanism for 15 selecting and presenting a filling yarn to said carrier.

8. A loom having in combination a lay, a reed, warp and filling yarn supplies, a shuttle, a yarn carrier adapted to be borne by the shuttle to pull a yarn across the lay, and means to remove the carrier from the shuttle and re-thread the carrier with yarn as the shuttle completes each traverse across the lay and then return said carrier to said shuttle as the shuttle begins each traverse across the lay, said means for removing said carrier from said shuttle and returning it thereto being adapted to enter into 25 said shuttle, said shuttle having resilient gripping means to receive and hold said carrier therein.

9. A loom having in combination a lay, a reed, warp and filling yarn supplies, a shuttle, a yarn carrier adapted to be borne by the shuttle to pull a yarn across the lay, 30 and means to remove the carrier from the shuttle and re-thread the carrier with yarn as the shuttle completes each traverse across the lay and then return said carrier to said shuttle as the shuttle begins each traverse across the lay, said filling yarn being supplied from behind the 35 lay and through the reed.

10. A loom which comprises means for supplying a group of warp yarns, means for forming the warp yarns into a series of sheds, a shuttle, means for moving the shuttle alternately in opposite directions through successive sheds, a lay supporting the shuttle in its flight and having a reed, means for reciprocating the lay, means for supplying at least one filling yarn at each side of the group of warp yarns, a yarn carrier transported by the shuttle and having means for retaining a filling yarn supplied at either side of the shed and pulling it through the shed to the opposite side, means adjacent the path of the shuttle for removing the carrier from the shuttle near the end of its flight in either direction and holding the carrier in position to be taken away by the shuttle 45 in its return flight, and means operating the retaining means, when the carrier is in a removing means, to cause the retaining means to release the filling yarn pulled through the shed and to retain another filling yarn being supplied adjacent the point of release, said removing 50 means including receivers mounted on the lay at opposite ends thereof in position to remove the carrier from the shuttle approaching the end of its flight in either direction and to hold the carrier in position to be engaged by the shuttle near the start of its return flight, 55 each receiver being an elongated bar having recess in its forward end for receiving the carrier and means being provided for reciprocating the bar longitudinally.

11. The loom of claim 10 in which the carrier has a body with a passage extending from end to end, the yarn 60 retaining means including a bar mounted for endwise movement in the passage and having a hook at each end, the bar being of such length that, when one hook is in the passage, the other is exposed, and the means for causing the retaining means to release one filling yarn and retain another include a member having an abutment surface and means for moving the receiver holding the carrier to cause the exposed hook of the bar to engage the abutment surface and be moved into the passage.

12. A loom which comprises means for supplying a group of warp yarns, means for forming the warp yarns into a series of sheds, a shuttle, means for moving the shuttle alternately in opposite directions through successive sheds, a lay supporting the shuttle in its flight and having a reed, means for reciprocating the lay, means for supplying at least one filling yarn at each side of the group of warp yarns, a yarn carrier transported by the shuttle and having means for retaining a filling yarn supplied at either side of the shed and pulling it through the shed to the opposite side, means adjacent the path of the shuttle for removing the carrier from the shuttle near the end of its flight in either direction and holding the carrier in position to be taken away by the shuttle in its return flight, and means operating the retaining means, when the carrier is in a removing means, to cause the retaining means to release the filling yarn pulled through the shed to retain another filling yarn being supplied adjacent the point of release, said shuttle being formed with a lengthwise passage, into which the receiver may enter, and having resilient gripping means for holding the carrier in the passage, said gripping means on the shuttle including a pair of elements for frictionally engaging opposite surfaces of the carrier and resilient mountings for the elements urging them toward each other.

13. A loom which comprises means for supplying a group of warp yarns, means for forming the warp yarns into a series of sheds, a shuttle, means for moving the shuttle alternately in opposite directions through successive sheds, a lay supporting the shuttle in its flight and having a reed, means for reciprocating the lay, means for supplying at least one filling yarn at each side of the group of warp yarns, a yarn carrier transported by the shuttle and having means for retaining a filling yarn supplied at either side of the shed and pulling it through the shed to the opposite side, means adjacent the path of the shuttle for removing the carrier from the shuttle near the end of its flight in either direction and holding the carrier in position to be taken away by the shuttle in its return flight, and means operating the retaining means, when the carrier is in a removing means, to cause the retaining means to release the filling yarn pulled through the shed and to retain another filling yarn being supplied adjacent the point of release, said carrier including a body having a passage extending lengthwise from end to end thereof, a shoe mounted in the passage with its ends at the ends of the passage, and a bar movably disposed in the passage with one face in contact with the shoe, the bar having a hook at each end and being of such length that, when one hook is in the passage, the other is exposed.

14. A loom which comprises means for supplying a group of warp yarns, means for forming the warp yarns into a series of sheds, a shuttle, means for moving the

shuttle alternately in opposite directions through successive sheds, a lay supporting the shuttle in its flight and having a reed, means for reciprocating the lay, means for supplying at least one filling yarn at each side of the group of warp yarns, a yarn carrier transported by the shuttle and having means for retaining a filling yarn supplied at either side of the shed and pulling it through the shed to the opposite side, means adjacent the path of the shuttle for removing the carrier from the shuttle near the end of its flight in either direction and holding the carrier in position to be taken away by the shuttle in its return flight, and means operating the retaining means, when the carrier is in a removing means, to cause the retaining means to release the filling yarn pulled through the shed and to retain another filling yarn being supplied adjacent the point of release, a heddle for controlling each filling yarn and separate means for raising and lowering the respective heddles, a heddle in its lower position holding its yarn in position 10 to be engaged by the retaining means on the carrier.

15. The loom of claim 14 in which the filling yarn heddles are to the rear of the reed and the filling yarns pass through the splits of the reed.

16. A loom as claimed in claim 1 in which said means for moving said filling yarn fixing means and said carrier relatively to each other includes means for moving said receivers towards their respective filling yarn fixing means whereby to move said filling yarn fixing means and said carrier relatively to each other as aforesaid.

17. A loom as claimed in claim 1 in which said filling yarn retaining means of said carrier includes hooked means on said carrier for engaging a filling yarn as it extends from the selvage edge of cloth being woven to its respective supply means and means for severing a filling yarn engaged by said hooked means adjacent its point of engagement with said hooked means to form a cloth free end.
